DES. 1951

Russell Wheeler and Stephen A. Bailey, of Utica, N.Y.
Letters Patent. No. 1951 Dated June 7th, 1864.
Design for an Agricultural Furnace.

The schedule referred to in these Letters Patent and making part of the same.

To all whom it may concern:

Be it known that we, Russell Wheeler and Stephen A. Bailey, of the City of Utica, in the County of Oneida and State of New York, have invented a new and improved design for an Agricultural Furnace; and we do hereby declare that the following is a full and exact description thereof, reference being had to the accompanying drawings and to the letters of reference marked thereon.

The nature of our invention consists in a new design for an Agricultural Furnace as represented in the accompanying drawings.

To enable others skilled in the art to make and use our invention, we will proceed to describe its design and construction. The general form and design is represented by Fig. 1. The manner in which the upper edge of the kettle sets in the upper rim of the furnace is represented by A and B. Figs. 1 & 2. The upper rim of the furnace is represented by B Fig. 3. The moulding on the front above the doors is represented by C. Figs. 1 and 4. The moulding upon the edge of the hearth is represented by F. Figs. 1 and 5. The moulding upon the four corners is represented by E. Figs. 1 and 6. The mouldings upon the sides are represented by G. Figs. 1 and 7, and also by D. Figs. 1 and 8. The whole is of cast iron and the figures and letters referred to above are on the accompanying drawings.

What we claim as our invention, and desire to secure by Letters Patent, are, the form and design of an Agricultural Furnace as above described and represented.
